UNITED STATES PATENT OFFICE

2,451,626

AIR FLOW REGULATING VALVE

William A. Marshall, Jr., Chicago, Ill., assignor
to Stewart-Warner Corporation, Chicago, Ill.,
a corporation of Virginia

Application February 12, 1945, Serial No. 577,377

2 Claims. (Cl. 137—152)

1

The present invention relates to air flow regulating valves and more particularly to an improved combustion air regulator for controlling the supply of combustion air to the combustion chamber of an internal combustion heater and particularly aircraft heaters.

One of the primary objects of the present invention is to provide a new and improved means for controlling the rate of supply of air for combustion to an internal combustion heater.

Another object of the present invention is to provide a new and improved combustion airflow regulator for internal combustion heaters wherein the rate of supply of air for combustion is regulated by means directly responsive to the pressure of the combustion air supplied to the heater.

Another object of the present invention is to provide a new and improved means for controlling the rate of supply of combustion air to an internal combustion heater wherein the rate of supply may be readily regulated.

A further object of the present invention is to provide a new and improved air flow regulating valve, and especially one which can readily be applied to different types or sizes of apparatus, as for instance, different sizes or types of heaters.

Other objects and advantages of the present invention will become apparent from the ensuing description in the course of which reference is had to the accompanying drawings, in which.

Figure 1 is a fragmentary longitudinal cross-sectional view of a portion of an internal combustion heater equipped with the combustion air regulator of the present invention;

Figure 2 is a side-elevational view partly broken into section to illustrate essential heater elements and the air regulating valve;

Figure 3 is an end elevational view of the apparatus illustrated in Figure 2, the view being taken along the line 3—3 of Figure 2;

Figure 4 is a plan view of the movable valve member, the view being taken along the line 4—4 of Figure 2; and

Figure 5 is an end elevational view of the valve member illustrated in Figure 4, the view being taken along the line 5—5 of Figure 4.

In heaters, and particularly those designed for use on aircraft, considerable difficulty has been encountered in maintaining an adequate and yet not excessive supply of air for combustion in the

2

combustion chamber. This difficulty is particularly pronounced in heaters in which the mixing of the fuel and air takes place within the combustion chamber, i. e., in heaters in which the fuel is supplied directly into the combustion chamber. The air is supplied to the heater under pressure and generally through a ram-type inlet port with the result that the pressure varies with the speed of the aircraft. Thus, as the speed of the aircraft varies, the velocity and pressure of the air varies, with the result that the amount (weight) of air supplied to the heater varies.

These difficulties are avoided in a simple and efficient manner through the use of my invention which comprises, in the main, a novel combustion air flow regulator or regulating valve capable of supplying a predetermined quantity of air to the combustion chamber under varying speeds. In the embodiment of the invention about to be described, the valve is so constructed and arranged that a desired substantially constant amount of air is supplied to the heater under varying speeds. For example, the amount of air thus supplied to the heater may be about 3 pounds per minute.

Referring now to the drawings, and especially to Figures 1 and 2, it may be noted that the heater has been indicated as a whole by reference character 10. It includes an outer metallic casing 12 within which is mounted a spiral type heat exchanger unit 14 at the upstream end (the left end as viewed in Fig. 1) of which is mounted a valve and combustion chamber assembly 16 constructed in accordance with the present invention. The assembly includes a combustion air flow regulating valve 18 including fixed and movable members to be described in detail hereinafter and structure defining a combustion chamber 20 located centrally and at the upstream end of the heat exchanger.

The heat exchanger and its associated combustion chamber may be of various types and that illustrated in the drawings is one of a type with which the present invention may be utilized. Heat exchangers of this general character are disclosed and claimed in the following copending applications, all of which are assigned to the assignee of this invention: Application of William C. Parrish, Serial No. 490,162, filed June 9, 1943 and issued as Patent No. 2,432,929, dated December 16, 1947; application of William C. Parrish,

Serial No. 494,155, filed July 10, 1943; and application of Arthur R. Collins, John H. Leslie II, and Charles T. Novak, Serial No. 553,150, filed September 8, 1944.

The heat exchanger unit 14 is mounted substantially centrally of casing 12. Part of the air entering the upstream end of the casing is utilized as combustion air and flows to the combustion chamber in an amount determined by the air regulating valve 18 while part flows past the heat exchanger and is heated by the products of combustion. The products of combustion flow from the central combustion chamber 20 through a spiral passageway 22 and are exhausted through an exhaust connection 24 located at the bottom of the heater and secured to the casing as by a flanged collar 26.

The air to be heated flows lengthwise of the heat exchanger through a passageway 28 having a generally spiral cross-section. Suitable spacers are located in this passageway to provide the desired spacing and to hold the heat exchanger in assembled relation. The construction of the heat exchanger of the spiral type is more fully disclosed in the aforesaid Patent No. 2,432,929.

The combustion chamber includes a generally conical end member 32 suitably secured to the central part of the heat exchanger and supporting at its narrow upstream end a fuel supply fitting 33 detachably secured, as by screws, to a fuel supply and igniter fitting 34, preferably having generally the shape of a figure 8. The end member 32 is provided with a series of spaced apart apertures 35 through which the combustion air flows into the combustion chamber.

Liquid hydrocarbon fuel is supplied under pressure and preferably in a substantially constant quantity to the combustion chamber through a fuel supply line 36 and a spray nozzle 38 detachably secured to the fitting 33. The fuel supply line 36 is secured to a hollow extension 40 of the fitting as by a coupling 42. The nozzle 38 is secured to a central hollow portion 43 of the fitting in such manner that fuel is injected into the combustion chamber substantially centrally lengthwise of the same. A suitable fuel filter 44 is secured to the inner end of the nozzle. An igniter 46 of the hot wire type is secured in good heat conducting manner to a downwardly extending portion 48 of the figure 8 shaped fitting 34. Electrical energy is supplied to the igniter through a conductor 50. The inner end of the igniter projects into the combustion chamber a slight distance through an aperture 52 in the conical member 32. The igniter is enclosed within a closure tube 54 suitably secured as by welding or the like to the conical member 32 and to the extension 48 of the fitting 34. The foregoing fuel supply and igniter arrangement is more fully described and also claimed in the co-pending application of Lynn A. Williams, Jr., Serial No. 509,161, filed November 6, 1943, and assigned to the assignee of this application.

The fluid line 36 and conductor 50 are led to the fitting 33 through an airtight seal comprising a rubber washer 56 adapted to be compressed between a pair of washers 58 and 60. The compression is effected by rotation of an externally threaded sleeve 62 within an internally threaded bushing 64 suitably secured to a cylindrical casing defining member 66 forming a part of the combustion chamber assembly 16 and through which the combustion air flows on its way to the combustion chamber. The outer casing 12 is sealed by a rubber washer 68 adapted

to be compressed by a flange 70 secured to the upper end of the sleeve 62.

The combustion air flowing through cylindrical portion 66 is directed to the combustion chamber 5 by a short convergent tube 12 secured to the inner end of casing 66 and between the central portion of the heat exchanger and the inner end of tubular portion 32 of the combustion chamber.

The air valve 18 includes a stationary centrally 10 apertured housing 74 having a smaller diameter upstream inlet end 76 and a larger diameter downstream end 78 and detachably secured in airtight manner to the adjacent end of casing 66. The airtight connection can be effected by 15 means of a flanged collar 80 secured to the interior of casing 66 and supporting sealing gasket 82 between it and the end 78 of the stationary valve member 74. The latter is detachably secured to casing 66 by means of a plurality of 20 bolts 84 passing through bosses 86 in the stationary member and through brackets 88 secured to the exterior of the casing (Figs. 2 and 3).

Liquid fuel collecting at the bottom of casing 66 is drained therefrom through a connection 90 leading from the bottom of the casing to the exhaust, as best illustrated in Figure 1.

The air valve 18 of the present invention may be constructed readily and economically, may be readily attached to different sizes and types of units, and is actuated directly in response to the pressure of the air supply. It comprises a movable restriction valve member 92 so constructed and arranged that as the air pressure increases it gradually restricts the flow of the air to the combustion chamber by gradual closure of the central inlet port 94 at the small diameter end 76 of the fixed valve housing 74. The movement of the valve member 92 is restrained by a helical spring 96 which serves normally to maintain it in its maximum flow position. This position is determined by a stop bolt 98 adapted to be secured in a predetermined adjusted position by a stop nut 100. The stop bolt is secured at the upstream end of a yoke 102 including three spaced apart 40 arms 104, the downstream ends of which are secured to bosses 106 formed on valve housing 74 by suitable means such as the screw bolts 107.

The movable valve member 92 is guided by a supporting and adjusting shaft 106' adjustably 50 secured to an inwardly extending boss 108 formed integral with the housing 74. The inner end of the shaft is threaded as indicated by reference character 110, whereby the shaft may be locked in adjusted angular position by means of the 55 lock nuts 112 at the outer extremity thereof and adapted to engage one side of the boss 108.

The movable valve member 92 is preferably made as an aluminum die casting. In order that it will not wear unduly in use, a sleeve 114 of 60 suitable bearing material is mounted within the central opening. A stop engaging button 116 is mounted at the end of the valve for engagement with the stop bolt 98.

The movement restraining spring 96 is held 65 within an annular recess 118 cast in the valve and a cup-like retainer 120 adjustably mounted upon a tubular externally threaded retainer support 122 pinned, as by a pin 124, for rotation with the shaft 106'. Rotational or angular movement 70 of the retainer 120 is resisted by a pin 126 carried in the bottom wall of the retainer and slidably extending into bore 128 in the boss 108 so that the retainer may be moved axially of the shaft to adjust the pressure of the spring 96. The tubular support 122 bears against the opposite side of the

boss 108 from lock nuts 112 whereby the shaft is held in adjusted position.

The movement of the valve member 92 relative to the inlet port 94 regulates the flow of air to the combustion chamber. The maximum flow is determined by the adjustment of the stop bolt 98, which determines the extreme limit of movement in port opening direction. The variation in effective port size in response to movement of the movable valve member is controlled by the spring 96 and the particular shape of the port end of the valve member. In the indicated construction the effective end of the movable valve member includes diametrically opposite similarly configured surfaces 130 and 132. The two surfaces are separated by axial extensions 134 of short angular extent. Each of the portions 130 and 132 includes gradually receding portions indicated by reference characters 130A, 130B and 132A and 132B. Each also includes sharply receding portions 130C and 132C which are of short angular extent as compared to the gradually receding portions. The gradually receding portions may have an angle of about 6 degrees with respect to a plane normal to the axis while the sharply receding portions may include an angle of about 20 degrees. These portions form slot-like ports in the skirt of the movable valve member 92.

In operation, the pressure of the air supply determines the position of the movable valve member and the effective port size. The spring 96 normally maintains the movable valve member in its outermost position whereat the stop bolt 98 bears against the stop button 116 in the valve. As the air pressure increases the spring 96 is compressed and member 92 moves downstream to close more or less of the inlet opening between the housing 74 and the valve member 92 depending upon the pressure to maintain a substantially constant (or other desired) flow of air to the combustion chamber.

In initially adjusting the valve, the maximum flow adjustment is first made by determining the outermost position of member 92 by the stop bolt 98. This is done with the spring 96 loaded to some desired value and at some lower air pressure. Then the valve is subjected to a higher air pressure and the adjusting shaft 106 is rotated to load the spring to a desired extent whereat the flow at the pressure (which may be the maximum pressure) is at the desired value. The initial position should be such that variations in air pressure move the movable valve member proportionately to the pressure. Otherwise, as would be the case if the movable member were upstream beyond an effective flow control position, the control would not be proportional to the variations in pressure.

Different springs could be used and, as already indicated, the effective port controlling surfaces may be changed to give the desired control over the flow of combustion air to the combustion chamber.

While a preferred embodiment of the present invention has been described in detail, it should be understood that the details thereof are not to be construed as limitative of the invention except in so far as set forth in the accompanying claims.

Having thus described my invention, what I claim as new and desire to secure by Letters Patent of the United States is:

1. A combustion air regulator for an internal combustion heater which has a source of air of

positive but variable pressure for diverting to the combustion chamber of the heater a constant quantity of air from the air flowing from said source, comprising: means forming a housing, an inlet to said housing, a generally cup-shaped valve member having a head against which the air entering said inlet impinges and having a cylindrical skirt adapted to project into said inlet, said skirt having ports therethrough, said valve being telescopically movable with respect to said inlet to vary the effective area of said ports and thereby to control the flow of air into said housing, said valve having an outer diameter slightly smaller than the diameter of said inlet so that when said valve is telescoped into said inlet there will be a narrow annular space between the outer cylindrical surface of said valve skirt and said inlet, a shaft axially disposed with respect to said inlet for supporting said valve member and guiding the movement thereof, a cup-shaped spring retainer on said shaft having a skirt oppositely disposed with respect to the skirt on said valve and projecting thereinto, and a spring positioned about said shaft and reacting between the inner side of the head on said valve and the bottom of said retainer, said spring being adapted to yield upon variation in the pressure of the air on said valve member proportionately to the pressure, whereby the valve member is adjusted to a position to maintain constant the amount of air flowing into said housing, and said retainer being movable axially of said shaft when the latter is rotated for adjusting the tension of said spring.

2. A combustion air regulator for an internal combustion heater which has a source of air of positive but variable pressure for diverting to the combustion chamber of the heater a constant quantity of air from the air flowing from said source, comprising: means forming a housing, an inlet to said housing, a generally cup-shaped valve member having a head against which the air entering said inlet impinges and having a cylindrical skirt adapted to project into said inlet, said skirt having ports therethrough, said valve being telescopically movable with respect to said inlet to vary the effective area of said ports and thereby to control the flow of air into said housing, said valve having an outer diameter slightly smaller than the diameter of said inlet so that when said valve is telescoped into said inlet there will be a narrow annular space between the outer cylindrical surface of said valve skirt and said inlet, a shaft axially disposed with respect to said inlet for supporting said valve member and guiding the movement thereof, a cup-shaped spring retainer on said shaft having a skirt oppositely disposed with respect to the skirt on said valve and projecting thereinto, a spring positioned about said shaft and reacting between the inner side of the head on said valve and the bottom of said retainer, said spring being adapted to yield on variation in the pressure of the air on said valve member proportionately to the pressure, whereby the valve member is adjusted to a position to maintain constant the amount of air flowing into said housing, means for adjusting the tension of said spring including means on said shaft and rotatable therewith for forming a threaded connection between said shaft and said retainer to impart axial movement to said retainer relative to said shaft upon angular movement of said shaft, means including said threaded connection forming means for locking said shaft against angular movement, and means aligned with said shaft for limiting

7

axial movement of said valve member outwardly
of said inlet.
